FIG. 3.

UNITED STATES PATENT OFFICE.

LEINER T. SKRIVSETH AND JACOB N. SKRIVSETH, OF BEMIDJI, MINNESOTA.

FANNING-MILL.

1,056,464.

Specification of Letters Patent. Patented Mar. 18, 1913.

Application filed May 23, 1912. Serial No. 699,272.

To all whom it may concern:

Be it known that we, LEINER T. SKRIVSETH and JACOB N. SKRIVSETH, citizens of the United States, residing at Bemidji, in the county of Beltrami and State of Minnesota, have invented certain new and useful Improvements in Fanning-Mills, of which the following is a specification, reference being had to the accompanying drawings.

This invention relates to new and useful improvements in fanning mills for separating grain, the object of the invention being to provide certain improvements whereby the operation of cleaning and separating certain kinds of seeds may be simplified and the labor connected therewith reduced to a minimum in addition to more thoroughly cleaning and separating the seeds.

Another object of the invention is to provide a fanning mill of this character wherein all the light seeds and foreign particles are blown from the grain before it enters into the grading screens, which will enable the mill to do more and cleaner work than the fanning mills in use at the present time.

A further object of the invention is to provide a fanning mill which will possess advantages in points of efficiency and durability, is inexpensive to manufacture and at the same time is simple in construction and operation.

With the above and other objects in view, the invention consists in the novel features of construction and the combination and arrangement of parts hereinafter more fully described, pointed out in the claim, and shown in the accompanying drawings in which,

Figure 1 is a side elevation of a fanning mill constructed in accordance with our invention. Fig. 2 is a top plan view. Fig. 3 is a vertical sectional view. Fig. 4 is a sectional view on the line 4—4 of Fig. 3.

Referring more particularly to the drawings, 1, 2, 3, and 4 indicate the upwardly-extending posts of the frame which supports the various mechanisms, said posts being arranged in pairs at each side of the machine with the cross members 5 and 6 connecting the respective pairs of posts at their lower ends, the upper ends being suitably connected by means of the hopper 7 and the intermediate portion of the posts are connected by the cross beams 8. Mounted upon one of the pairs of posts are the bearings 9 in which is mounted the fan shaft 10, to

which latter are secured the radial fan arms 11, and on the ends of said fan arms are secured the respective fan blades 12. Mounted upon the other pairs of posts is a gear wheel 13 which is suitably connected to a similar gear 14, mounted upon the end of the fan shaft 10, by means of the sprocket chain 15, the gear 14 is operated by means of the crank handle 16.

Arranged within the frame and having one end suspended by means of the pivotally mounted hangers 17 is the upper vibrating shoe 18, the other end of said shoe being pivotally connected to the upper end of the link bars 19, which are pivotally mounted upon the cross beams 8. The lower ends of the link bars 19 are pivotally connected to and adapted to support one end of the grading screens 20, said grading screens being arranged in superimposed relation and suitably secured to the side bars 21. Pivotally secured to one of the pairs of the posts and having one of their ends pivotally connected to the outer end of the pitman 22 are the links 23, the inner ends of said pitman being pivotally secured to the ends of the shaft 10. The links 23 are pivotally secured to the front end of the screens 20 by means of the pins 24 so that the screens 20 will be vibrated when motion is imparted to the gear wheel 13. Arranged transversely across each of the screens 20 and having their ends secured to each side thereof are the supporting rods 25. Retaining plates 26 are provided, having one end curved upwardly as shown at 27 to form a sleeve 27' which is pivotally mounted upon the rods 25 so that the body portion of the plate rests upon the screens 20 to prevent the oats, large sticks and other foreign particles from standing on end so that the same will not pass through the screens 20 to the lower grading screen 28. It will be understood that the grading screens 20 will be so arranged that the fine screen wire is arranged at the bottom and the coarser screen at the top so that as the grain passes from the screens the good grain will drop down through the finer screens on to the screen 28, the oats, sticks and other foreign particles passing out at the front end of the mill as shown at 29 while the good grain will be discharged to the rear of the machine by means of the screen 28. The screen 28 is supported at one end by means of the hangers 30 which are pivotally secured to the posts 2 and 4, while

the other ends of the hangers are adjustably and pivotally secured to the rear end of the screen 28. The front end of the screen 28 is pivotally secured to the lower ends of the 5 links 24.

In separating grain by the use of our improved fanning mill, the threshed grain is placed in the hopper 7 and fed on to the shoe 18 by means of the adjustable feed 10 board 31 said board being adjusted by means of the crank 32 so that the flow of grain from the hopper on to the shoe 18 will be easily controlled by the operator. An adjustable blast reflecting board 33 is 15 provided, the forward end of which is adapted to be raised or lowered to regulate the blast of the fan. An adjustable end board 34 is arranged in the front end of the shoe 18 and adapted to be vertically adjusted according to the flow of grain from the hopper. 20 The grain being placed in the hopper 7 flows from the hopper on to the shoe 18, and as it flows from the hopper on to the shoe the blast from the fan at the rear of the machine 25 will separate the chaff hulls and other light particles from the grain, the grain passing through the shoe down on to the grading screens 20 where the grain is separated from the oats, sticks and other foreign particles. 30 As the grain drops from the shoe 18 on to the screens 20 it will drop so as to go under the plates 26 and as it moves forward toward the front end of the screen it passes beneath the plates 26, the weight of the plates preventing 35 the oats, sticks and other foreign particles, when cleaning wheat, from rising on end by the movement of the screens. Thus it will be seen that while the grain is separated from the small seeds and other foreign 40 particles, the plates 26 will not allow any of the foreign particles to pass through the screens 20 on to the screen 28, whereas the fanning mills in use at the present time allow a great deal of the foreign particles to 45 escape with the good grain, while with the use of our improved fanning mill, all of the good grain will be saved and at the same time will be separated from the small seeds and the foreign particles. The screen 28 is 50 to be of a fine wire mesh so that the grain will pass off the rear end of the same while the

small seeds and other foreign particles pass through the screens on to the bottom of the mill.

From the above description taken in connection with the drawings it will be apparent that we have provided a simple and efficient device whereby threshed grain can be quickly and easily separated from the chaff and other foreign particles, and at the same time will be inexpensive to manufacture.

While we have shown and described the preferred form of our invention it will be obvious that various changes in the details of construction and in the proportions may be resorted to for successfully carrying our invention into practice without sacrificing any of the novel features or departing from the scope thereof.

What we claim is:-

In a device of the character described, the combination with standards, a hopper mounted on the upper ends of said standards, a shaft rotatably mounted in said standards, a reciprocating grain shoe arranged beneath said hopper, grading screens arranged for reciprocation beneath said grain shoe, a second reciprocating grain shoe arranged beneath said grading screens, a pitman rod connected at one end to said shaft, a link bar pivotally mounted intermediate of its ends on one of said standards, one end of said link bar being pivotally connected to said second reciprocating grain shoe, the other end of said link bar being pivotally connected at its extremity to the opposite end of said pitman rod and also pivotally connected at said other end inwardly of its extremity to said grading screens, and a second link bar pivotally connecting said grading screens and the first mentioned grain shoe, whereby the grading screens will be reciprocated in a direction opposite from the grain shoes when said shaft is rotated.

In testimony whereof we hereunto affix our signatures in the presence of two witnesses.

LEINER T. SKRIVSETH.
JACOB N. SKRIVSETH.
